UNITED STATES PATENT OFFICE.

STEPHEN A. HORTON, OF CLARKSVILLE, ASSIGNOR TO THE HORTON DEEP AND ARTESIAN WELL COMPANY, INCORPORATED, OF DALLAS, TEXAS.

WELL-DRILLING APPARATUS.

SPECIFICATION forming part of Letters Patent No. 554,820, dated February 18, 1896.

Application filed September 7, 1894. Serial No. 522,380. (No model.)

To all whom it may concern:

Be it known that I, STEPHEN A. HORTON, a citizen of the United States, residing at Clarksville, in the county of Red River and State of 55 Texas, have invented a new and useful Well-Drilling Apparatus, of which the following is a specification.

My invention relates to well-drilling apparatus for boring Artesian and other wells, and 10 the objects in view are to provide simple, efficient and durable means for expanding or spreading the reamer-blades after the bit-carrying devices have been lowered sufficiently to arrange the reamer-blades below the plane 15 of the lower end of the tubular drill-rod; to provide expanding devices actuated by the pressure of the water admitted to the drill-rod for the purpose of freeing the boring-blades from cuttings, such pressure of the 20 water as above being assisted by gravity; to provide means for supporting the sections of cable by which the drill-bit-carrying parts are suspended and lowered into the drill-rod, whereby as successive sections of the drill- 25 rod are added similar sections of the supporting-cable, said sections being of equal length with the sections of drill-rod, may be attached; to provide improved means for securing the reamer-blades in the reamer-stock, and to 30 provide an improved expandable packer arranged upon the drill-bit-carrying parts and adapted when expanded to fit snugly in the drill-rod and prevent water admitted to the drill-rod from passing down around the core 35 and deflect it into the bore of the core, for a purpose hereinafter explained.

Further objects and advantages of the invention will appear in the following description, and the novel features thereof will be 40 particularly pointed out in the appended claims.

In the drawings, Figure 1 is a view of a well-drilling apparatus embodying my invention, the core, bit, reamer, and connected 45 parts being shown in side elevation and the drill-rod in section. Fig. 2 is a detail view of the cutting device, core, and packer, the packer and the upper end of the core being shown in section. Fig. 3 is a detail sectional 50 view of the reamer and connected parts, showing the means for expanding the reamer-

blades. Fig. 4 is a similar view of a slightly-modified form of means for communicating motion to the reamer-blades from the expansion devices. Fig. 5 is a similar view showing another modified form of reamer-blade-expanding devices. Fig. 6 is a detail sectional view on the line 6 6 of Fig. 2, to show the channels or ports whereby water flows from the interior of the core to the outlet-perforations in the drill-bit when the reamer-blades are expanded. Fig. 7 is a detail sectional view on the line 7 7 of Fig. 3, to show means for mounting the reamer-blades in the reamer-stock. Fig. 8 is a detail sectional view of the 65 upper terminal section of the drill-rod, showing the upper section of the supporting-cable and the device for suspending such cable in the drill-rod within reach of the operator during the drilling operation. 70

Similar numerals of reference indicate corresponding parts in all the figures of the drawings.

1 designates a tubular drill-rod formed in detachable sections which are connected at 75 their contiguous extremities by means of couplings 2, the lower section, 3, of the drill-rod forming a bit-socket and being constructed with interior ribs 4 for engagement with pockets 5 formed on the surface of the 80 core 6, said pockets being provided by notches cut in lateral extensions 7 of the exterior ribs 8 and having beveled lower sides, as shown at 9. All of this construction is clearly illustrated and described in my application, Serial 85 No. 507,891, filed April 17, 1894. These cores are hollow or tubular in construction, and attached to the lower extremity thereof and having exterior ribs 10 arranged in alignment with the exterior ribs on the core is a reamer, 90 having a stock 11 and expandable blades 12 arranged in diametrical or transverse alignment. When the parts are in operative position, as shown in Figs. 1 and 3, said reamer-blades are expanded, and their outer ends 95 project beyond the surface of the drill-rod, and beyond the outer surface of a wear-sleeve 13, which is threaded upon the lower extremity of said drill-rod, whereby as the drill is operated said blades enlarge the opening 100 formed by the usual drill-bit to form a hole of sufficient diameter to receive the drill-rod.

These blades 12 are pivotally mounted in a transverse slot 14 extending diametrically through the reamer-stock, and upon opposite sides of the plane of said slot and arranged 5 vertically, as shown in Fig. 6, are ports or channels 15, whereby communication is established between the interior of the core and the socket 16 at the lower end of the reamer-stock. Threaded in this socket 16 is the 10 shank 17 of an ordinary flat-bladed drill-bit 18, the shank being bored, as shown at 19, and being provided with outlet-perforations 20 communicating with the bore 19, whereby water may pass from the interior of the core, 15 through the channels 15, bore 19, and perforations 20, to the space upon opposite sides of the blade of the drill-bit to remove cuttings and carry them upward outside of the drill-rod.

20 Mounted axially in the interior of the core is a piston head or plunger 21, fitting snugly in the bore of the core, the latter being counterbored or channeled at its lower end, as shown at 22, whereby when the piston-head 25 is in its lowered position, as shown in Fig. 3, water may pass from the interior of the bore to the space below the piston-head to communicate with the channels 15. Attached to the upper side of said piston head or valve 30 21 is a bar 23, and depending from said piston head or valve and operating in a guide-opening 24 in the upper end of the reamer-stock 11, is a stem 25, which is connected with the reamer-blades whereby a vertical 35 movement of the piston head or valve is communicated to the blades, to either expand or fold the same. The connection shown in Fig. 3 is accomplished by means of rack-teeth on the stem meshing with gear-segments on the inner ends of the blades, said inner ends 40 of the blades being rounded concentrically with their pivots.

The function of the bar 23 is to assist the 45 pressure of water upon the surface of the piston-head in expanding the blades, and in case the blades resist the downward pressure of the water and the bar the latter may be affected to accomplish the expansion by jarring the tubing. A similar connection between the stem of the piston head or valve is 50 shown in Fig. 4, wherein flexible ribbons or straps 26, connected at one end to the stem and at the other end to the rounded extremities of the blades, are employed; and it will be seen that when the piston head or valve is depressed by the admission of water to the 55 interior of the core such motion is communicated through the ribbons or straps to the blades and the operating extremities of the latter are swung outward.

60 In Fig. 5 I have shown still another modified form of my reamer-blade-expanding devices, the same consisting of a piston head or valve 27 mounted in a bore 28 in the reamer-stock 29, said bore being provided in its walls with grooves or channels 30, whereby when the piston head or valve is in its depressed posi-

tion water may pass from the interior of the bore 28 above the piston head or valve to the bore 19 in the drill-bit shank, and whereby 70 previous to the depression of said piston head or valve such flow of the water around the same is prevented, a stem 31 rising from the center of the piston head or valve into the space or slot 32, in which the reamer-blades 75 33 are mounted, and flexible ribbons or straps 34 connecting the upper extremity of the stem 31 with the rounded inner ends of the blades, said ribbons or straps and the manner of connecting the same to the blades being identical 80 with that shown in Fig. 4.

It will be seen that the only difference between the constructions shown in Figs. 4 and 5 is that in Fig. 5 the position of the piston head or valve and its stem is reversed, the piston head or valve proper operating in a bore formed in the reamer-stock, whereas in Fig. 4 the piston head or valve operates in the bore of the core. The constructions shown in Figs. 3 and 4 are preferable to that shown in Fig. 90 5, for the reason that the latter requires an extended reamer-stock, thus placing the bit at a considerable distance below the reamer-blades, whereas the former disposes the bit close to the frame of the reamer-blades. 95

Although not shown in the drawings, it will be understood that the reamer-stock shown in Fig. 5 is provided with perforations similar to those described in connection with Fig. 6 for conducting water from the interior of the core to the upper end of the bore 28 or the space above the piston head or valve 27.

From the above description it will be seen that the blades are mounted to swing through an arc of ninety degrees from a horizontal operative position downwardly to a vertical or folded position in which the blades are wholly concealed within the transverse opening or slot and as the blades fold downwardly they will be turned to their folded positions by 110 contact with the sides of a drill-hole when the drilling apparatus is elevated. The inner extremities of the blades are rounded concentric with their pivots in order to remain at their inner ends at the same interval in all 115 positions, this construction being adopted for the reason that the stem of the piston is extended between the rounded ends and it is desirable to maintain the stem permanently in engagement with both blades in all positions. The upper end or wall of the slot or opening in the reamer-stock serves as a stop to limit the upward swinging movement of the blades and thus prevent deflection when the apparatus is in use. 120

125 The means for mounting the reamer-blades in the slot or opening 14 comprise pivot-pins 35 fitting in horizontal openings 36 formed in the reamer-stock and intersecting said slot or opening 14, one end of the openings 36 being reduced, as shown at 37, and a locking-screw 38 being arranged in the opposite end of said opening to prevent the accidental displacement of the pin. The object of the reduced

portion 37 of this opening is to give access for a tool, whereby the pivot-pin may be driven out of the opening 36 after the removal of the locking-screw 38.

5 Arranged above the upper end of the core is the packer 39, comprising a shell or thimble 40 fitted upon an upper reduced extremity 41 of the core and capable of a limited vertical movement thereon. For this purpose said 10 shell or thimble is provided at its lower end with an interior shoulder 42, and a collar 43 is threaded upon the upper extremity of the reduced portion 41 of the core. This shoulder 42 by engagement with the lower edge of 15 the collar 43 limits the upward movement of the shell or thimble, and arranged upon a shoulder 44 provided by the reduction of the upper extremity of the core is a compressible ring 45, preferably constructed of rubber, 20 which in its normal shape is equal in exterior diameter to the core. This ring being arranged upon the shoulder 44 and around the reduced portion of the core is disposed in the path in the lower end of the shell or thimble 25 40, whereby a forcible depression of said shell or thimble will cause a horizontal flattening and consequent spreading of the ring, as shown in Fig. 1, to cause a snug fitting of the ring in the bore of the drill-rod to prevent 30 water from passing from the space above the packer to the space below the same outside of the core. The reduced portion 41 of the core is provided with a horizontal series of 35 inlet-perforations 46, and the shell or thimble is provided with a similar horizontal series of perforations 47, which communicate with an annular channel 48, formed in the inner surface of the shell or thimble, and therefore when the shell or thimble is depressed to expand 40 the packer this channel 48 is brought into communication with the perforations 46 and 47, whereby water admitted to the drill-rod at its upper end descends to the plane of 45 the packer and then is conveyed through the perforations 46 and 47 into the interior of the core to exert pressure upon the piston head or valve and thereby expand the reamer-blades and subsequently to pass through the 50 perforations in the bit to remove cuttings.

50 Threaded in the upper end of the shell or thimble 60 is a coupling 49, and connected to this coupling and by this coupling to the shell or thimble is the lower member, 50, of the drill-jars 51. The upper member, 52, of said 55 drill-jars is connected to the lower end of the auger-stem 53, and to the extremity of the latter is connected the rope-socket 54. It will be seen that the weight of the members above the movable part of the packer will be sufficient 60 to depress said movable part and cause the necessary lateral expansion of the packing-ring.

Connected to the rope-socket is the lower end of the lower section, 55, of rope, the adjacent ends of the rope-sections being connected by means of bull-rope couplings 56.

The upper section, 57, of the rope is connected by means of a rope-clamp 58 to the lower end of a chain 59, having an eye 60 attached to a holder or seat 61. This holder or seat is 70 perforated to allow water to pass from a point above the same to the interior of the drill-rod, and it is seated upon the upper extremity of the upper terminal drill-rod section. It has been stated that the sections of rope 75 correspond in length, approximately, with the drill-rod sections, and that a rope-section is attached each time a new length of drill-rod is applied, and hence the above-described means for holding the upper end of the rope 80 in position to be grasped by the operator.

The ring or eye 60 forms a convenient hand-hold, and when it is desired to attach another length of rope the upper end of the rope then in the drill-rod is drawn up, (the slack of said 85 rope being sufficient to provide for raising the upper extremity above the upper end of the terminal section of the drill-rod,) the additional section of rope is attached, the holding devices are connected to the upper end 90 of the new section of rope, and the additional drill-rod section is attached preparatory to lowering into the well.

Having thus described my invention, what I claim is—

1. The combination with a hollow drill-rod, of a reamer secured to the lower end of the drill-rod and having a stock provided with a transverse slot having a closed upper side, ports arranged upon opposite sides of the 100 plane of said slot and communicating at their upper ends with the bore of the drill-rod and at their lower ends with a socket formed in the lower end of the stock, a perforation being formed in the floor of the slot and communicating with the socket, whereby a portion of the water conveyed through the ports from the bore of the drill-rod to the socket is allowed to pass up through the perforation and escape by way of the transverse slot, pivotal blades arranged in the slot and adapted to fold thereinto or swing outward to project at their extremities beyond the outer surface of the stock, a stem arranged axially in the stock and extending between and permanently connected to both blades, and means for depressing the stem to extend the blades, substantially as specified.

2. A reamer having a stock provided with a transverse opening and pivotal blades 120 mounted to swing through an arc of ninety degrees from a horizontal downwardly to a vertical position within the opening, the blades being adapted to be folded by contact with the sides of a drill-hole during the ascent 125 of the drilling apparatus and having their inner ends rounded concentric with their pivots and spaced apart to form an interval between the inner ends of opposite blades, in combination with means for imparting downward motion to the inner ends of the blades, 130 said means including a gravity-actuated stem

extending between the rounded ends of the blades and permanently connected to both, substantially as specified. 3. The combination with a drill-rod, a hollow core, having an interlocking connection with the lowermost section of the drill-rod, and drilling devices attached to the lower end of the core, of a shell or thimble mounted to slide upon the reduced upper end of the core and provided with an interior shoulder 42, a collar removably fitted upon the extremity of said reduced portion to limit the upward movement of the shell or thimble by engagement with the shoulder thereof, a compressible packing-ring encircling the reduced portion of the core and resting upon a shoulder 44 at the lower extremity of the reduced portion, lateral perforations being provided in the shell or thimble and reduced portion of the core to register when the shell or thimble is in its depressed position, and elevating or hoisting devices connected to the shell or thimble, substantially as specified. 4. The combination with a drill-rod, a core having an interlocking connection with the lowermost section of the drill-rod, and a drill-bit, of a reamer having its stock interposed between the drill-bit and the core and provided with lateral slots or openings 14 in which the foldable blades 12 are mounted, said stock being provided with horizontal openings 36 intersecting the slots or openings 14 and reduced at one end as shown at 37, pivot-pins 35 fitted in said openings 36, and locking-screws 38 arranged in the openings at the op-

posite ends from the reduced portions, to prevent accidental displacement of the pivot-pins, the latter being accessible through the reduced portions of the openings to accomplish their displacement, substantially as specified.

5. The combination of a drill-rod, a core having an interlocking connection with the lowermost section of the drill-rod, drilling devices connected to the lower end of said core, a packing-ring arranged upon the core in contact with a shoulder thereof and adapted to be expanded by weight, a slidable shell or thimble connected to the core and adapted when depressed to engage and spread the packing-ring, drill-jars having their lower member connected to the said shell or thimble, an auger-stem connected to the upper member of the drill-jars, a sectional rope connected to the upper end of the auger-stem, the section of rope being detachably connected, and a holding device connected to the upper terminal rope-section, the same consisting of a perforated holder seated upon the upper extremity of the uppermost drill-rod section, and a chain connected to the upper rope-section, substantially as specified.

In testimony that I claim the foregoing as my own I have hereto affixed my signature in the presence of two witnesses.

S. A. HORTON.
